UNITED STATES PATENT OFFICE.

DALLAS A. BODIKER, OF DAYTON, OHIO.

MOVING-PICTURE MACHINE.

Application filed April 24, 1920. Serial No. 376,203.

To all whom it may concern:

Be it known that I, DALLAS A. BODIKER, a citizen of the United States, residing at Dayton, in the county of Montgomery and State of Ohio, have invented certain new and useful Improvements in Moving-Picture Machines, of which the following is a specification.

This invention relates to new and useful improvement in motion picture machines, and more particularly to an intermittent operating device for actuating the film of such a machine.

One object of the invention is to provide an intermittent operating mechanism which will be simple in its construction and operation, and which will be inexpensive to produce.

A further object of the invention is to provide such a device which can be easily adjusted to take up wear and thus prevent all lost motion.

A further object of the invention is to provide a device of this kind with which the driving member may be adjusted for the purpose of "Framing" the picture.

Other objects of the invention will appear as the device is described in detail.

In the accompanying drawings Fig. 1 is a side elevation of a motion picture machine embodying my invention, with the cover plate removed; Fig. 2 is a partial sectional view of the machine showing the intermittent mechanism in rear elevation; Fig. 3 is a sectional view taken on the line 3-3 of Fig. 2; Fig. 4 is a plan view of the intermittent drive; Fig. 5 is a side elevation of the intermittent drive; Fig. 6 is a front elevation of the intermittent drive; Fig. 7 is a development of a portion of the driving member; and Fig. 8 is a side elevation of a modified form of the intermittent drive.

Throughout the specification and drawings similar reference characters indicate corresponding parts.

Referring more particularly to the drawings, —1— represents a base from which upwardly extends a division plate —2— and a front plate —3— joined by a wall —4— which, together with a flange —5— form an inclosure for the lens and part of the film feeding mechanism. Also extending from the division plate —2— are upper and lower circular magazine flanges —9— and —10—

adapted to receive the well known reels, not shown, which are mounted on spindles —13— and —14—. The above described portions of the machine constitutes the housing, or casing which may be provided with a pocket —17— adapted to receive an electric motor (not shown) which may be used to drive the machine, but which forms no part of the present invention.

The reels —11— and —12— receive the film —18—, Fig. 7, which is unwound from the upper reel —11— and wound on the lower reel —12—. After passing from the reel —11— the film passes under an upper continuously rotating sprocket —20— and is then looped as at —21— and passed in front of a depressed plate —22— having an aperture —23— the same size as the picture on the film to be projected. The film then passes over an intermittent sprocket —24—, is then looped as at —25—, and passed over a continuously rotating sprocket —26— and into the magazine —10— where it is wound on the reel —12—. As is well known, the film —18— is looped as at —21— and —25— to permit that portion of the film being projected to be fed intermittently, while the remaining portions are unwound and wound continuously. The film —18— is held in engagement with the sprockets —20—, —24— and —26— by rollers —28—, —29— and —30— mounted on spring influenced frames —31— and —32— and —33— pivoted at —34—, —35— and —36— respectively. The film —18— is held against the aperture plate —22— by springs —37— mounted on a gate —38— pivoted at —34— and held in position by a latch —39—. When the latch —39— is released the gate may be swung back on its pivot to permit of the insertion or withdrawal of the film. The gate carries the roller —29— which is disengaged from its sprocket —24— when the gate is swung back. At the same time, the roller —28— disengaged from its sprocket by a projection —40— carried by the gate and is adapted to engage the frame —31—. The frame —33— of the lower sprocket —26— is elevated individually. The depressed or apertured plate —22— engages the film at the edges thereof and does not come in contact with that portion of the film provided with the picture, thereby preventing the emulsion becoming mutilated.

The lower sprocket —26— is mounted on a main drive shaft —41— journaled in the plates —2— and —3— and is provided with a hand crank, not shown, by which the machine may be manually operated. The end of the shaft —41—, opposite the crank, is provided with two chain sprockets —43— and —44— mounted on the side of the division plate opposite the sprocket —26—.

10 The sprocket —44— drives the "take-up" spindle —14— for the lower reel —12— through a chain —45—, a sprocket —46— and any well known form of slip mechanism —47— as is used in moving picture machines. The sprocket —43— drives the upper film sprocket —20— through a chain —48—, and a chain sprocket —49— mounted on a shaft —97—, journaled in the plate —2—, and upon which the upper film sprocket —20— is mounted. It is to be understood that the film sprockets are provided with teeth adapted to register with suitable perforations in the film in a well known manner.

15 20 25 To drive the sprocket —24— intermittently in either direction, the same is mounted on a shaft —51— journaled in the plates —2— and —3—. On the side of the plate —2— opposite the sprocket —24—, the shaft —51— is provided with a notched disc —52— which may be flanged as in the present instance. The said disc is, in fact, an intermittent gear. The disc or gear is provided with notches or recesses —53—, in the flange 30 35 40 45 50 55 thereof, there being as many recesses as there are intermittent movements given to the film sprocket —24— during one complete revolution of the said film sprocket. The recesses —53— are adapted to receive, and the gear —52— is adapted to be intermittently rotated, by a helical cam —54— mounted on a shaft —55—. The said cam —54— is provided with a continuation —56— adapted to hold the notched disc or gear —52— and sprocket —24— at rest when the cam —54— is out of engagement with the said gear. In one construction, the cam —54— and a continuation —56— are a part of a cylinder —57—, while in the construction shown in Fig. 14 the continuation is a mutilated disc —95— on a hub —63— and the cam is an offset therefrom. The length of the cam, in proportion to its diameter of revolution, determines the time consumed in shifting 60 65 70 75 80 85 90 95 100 105 110 115 120 125 130 and the amount of exposure of the film. In the drawings the parts are proportional for a cam of approximately one sixth of the diameter of revolution, but it is to be understood that this proportion may be increased or diminished as desired. The shaft —55— upon which the cam —54— is mounted is slidingly mounted in bearings —58— and —59— and is provided with a gear —60— in mesh with a gear —61— on a shaft —62— journalled in bearings —59— and —64—.

The shaft —62— is provided with a spiral pinion —65— in mesh with a spiral gear —96— mounted on the main drive shaft —41— and from which the cam —54— is driven. The intermittent sprocket —24— rotates at the same speed as the sprockets —20— and —26— but its angular speed is greater. The present construction makes eight intermittent movements, and feeds eight pictures for each revolution of the film sprockets, but it is to be understood that this ratio may be varied by changing the dimensions and proportions of the parts. To "frame" the film and to place successive pictures directly opposite the aperture —23—, the sprocket —24— is adapted to be moved, independently of the sprockets —20— and —26— by shifting the cam —54— and continuation —56— which rocks the sprocket —24—. This movement is accomplished by a lever —66— pivoted at —67— and the lower end of which lies between the cylinder —57— and gear —69— and is provided with pins —50— which enter an annular recess in the hub —63—. The lever —66— extends out of the housing to a position where it may be conveniently manipulated by hand.

While I have shown and described one embodiment of my invention I wish it to be understood that I do not desire to be limited to the details of the invention as various modifications may occur to a person skilled in the art.

Mounted in front of the film and in optical alignment with the aperture —23— is a projecting lens —84— which throws the picture on a screen (not shown). The rays of light projected by the lens pass out of the housing through an opening —85— in the flange —5—. The lens —84— is supported on a slide —86— mounted in guides —87— on the division wall —2—. The said lens —84— may be shifted along the optical axis, to focus the picture, by a screw —88— connected to the slide by a lever —89—. The screw —88— is provided with a head —90— on the outside of the casing. Mounted in front of the lens —84— is the shutter shown in detail in Fig. 12. In the present instance the said shutter is combined with the balance wheel and consists of a weighted rim —91— joined to a hub —92— by narrow spokes —93—. The said shutter and balance wheel are mounted on the shaft —62— and rotate once for each intermittent movement of the sprocket —24—. Mounted between two of the spokes —93— is a perforated screen —94—. The mechanism is so timed that the screen passes before the lens —84— and the projected light is intercepted during the time the picture is being changed and the sprocket —24— is receiving its intermittent movement. The screen —94— does not,

however, intercept all of the light, which expedient reduces flicker on the picture screen and eliminates eye strain.

The machine in the present instance is 5 adapted to utilize the special film shown in Fig. 13. The film itself is, however, of the conventional width and is provided with the standard perforations. The ordinary unexposed and undeveloped film, commercially available, may, therefore, be utilized. 10 In the present instance, the same space for a single picture on a standard film is used for four pictures which permits the film length, for the same subject, to be reduced 15 to one fourth, with a consequent saving in weight and a gain in portability. As will be seen from Fig. 13, the pictures are disposed on the film in two parallel rows, permitting the reels —11— and —12— to be 20 reversed without necessitating rewinding the film, the two rows of pictures being headed in opposite directions. Therefore, after the film has been run through once for one row of pictures, it is only necessary 25 to transpose the upper and lower reels to exhibit the other row. As the center of the pictures is to the side of the center of the film, the optical axis is placed off the center of the film sprockets and the aperture plate, 30 as will be seen from the position of the aperture —23— in Fig. 6.

Having described my invention, I claim:

1. In a picture projecting machine, an

intermittent feeding device comprising a disk having a circumferential flange extending at an angle to the plane thereof and provided with a series of notches spaced about the edge thereof, a driving member 35 rotatable about an axis transverse to the axis of said disk and comprising a circumferential rib adapted to enter the notches in said disk and having at one end thereof a spirally offset portion to impart movement to said disk, and means for imparting axial movement to said driving member to adjust said disk for framing the picture.

2. A film feeding device for a motion picture machine comprising an intermittent 45 sprocket, a disk connected with said sprocket and rotatable about the axis thereof, said disk having an annular flange extending substantially parallel with the axis thereof and provided with notches spaced about the 50 edge thereof, a shaft extending transversely to the axis of said disk, a driving member mounted on said shaft and comprising a spiral rib adapted to enter the notches of 55 said disk and having one end portion thereof spirally arranged to impart movement to said disk, means for rotating said shaft, and an actuating device for imparting axial movement to said driving member.

In testimony whereof I affix my signature.

DALLAS A. BODIKER.
